US00D960697S

(12) **United States Design Patent** (10) **Patent No.:** **US D960,697 S**
Baur et al. (45) **Date of Patent:** **** Aug. 16, 2022**

(54) **CONNECTING DEVICE**

(71) Applicants: **Lamello AG**, Bubendorf (CH); **Franz Baur**, Oberstaufen (DE); **Franz Josef Haser**, Oberstaufen (DE)

(72) Inventors: **Franz Baur**, Oberstaufen (DE); **Franz Josef Haser**, Oberstaufen (DE); **Philipp Seiler**, Arboldswil (CH); **Patrick Jeker**, Brislach (CH)

(73) Assignees: **Franz Baur**, Oberstaufen (DE); **Franz Josef Haser**, Oberstaufen (DE); **Lamello AG**, Bubendorf (CH)

(**) Term: **15 Years**

(21) Appl. No.: **29/607,477**

(22) Filed: **Jun. 13, 2017**

(30) **Foreign Application Priority Data**

Dec. 14, 2016 (EM) 003517234

(51) **LOC (13) Cl.** **08-08**

(52) **U.S. Cl.**

(57) **CLAIM**

The ornamental design for a connecting device, as shown and described.

DESCRIPTION

FIG. 1 is a perspective view of a first embodiment of a connecting device showing our new design;

FIG. 2 is a front view thereof;

FIG. 3 is a left side view thereof;

FIG. 4 is a rear view thereof;

FIG. 5 is a right side view thereof;

FIG. 6 is a top plan view thereof;

FIG. 7 is a bottom plan view thereof;

FIG. 8 is a perspective view of a second embodiment of a connecting device showing our new design;

FIG. 9 is a front view thereof;

FIG. 10 is a left side view thereof;

FIG. 11 is a rear view thereof;

FIG. 12 is a right side view thereof;

FIG. 13 is a top plan view thereof; and,

FIG. 14 is a bottom plan view thereof.

The broken lines in the drawings illustrate portions of the connecting device and form no part of the claimed design.

1 Claim, 14 Drawing Sheets
